UNITED STATES PATENT OFFICE.

GEORGE DOUTNEY, OF BROOKLYN, NEW YORK.

LOCK FOR ENVELOPS AND OTHER CONTAINERS.

1,384,604.

Specification of Letters Patent. Patented July 12, 1921.

Application filed July 6, 1920. Serial No. 394,182.

To all whom it may concern:

Be it known that I, GEORGE DOUTNEY, a citizen of the Dominion of Canada, and a resident of the city of New York, borough 5 of Brooklyn, in the county of Kings, and State of New York, have invented a new and useful Lock for Envelops and Other Containers, of which the following is a full, clear, and exact description.

- 10 This invention relates to envelops and containers of all kinds, and particularly to an improved lock therefor which will positively prevent any disengagement of the parts unless either the lock or some part of 15 the container is broken, and has for an object to provide a construction which is easily applied and which is positive in its actions either in a comparatively stiff container or in a flexible container.
- 20 Another object of the invention is to provide a lock which is particularly adapted for envelops in which the locking means are so arranged that they will be out of sight when in an interlocked position.
- 25 A still further object of the invention is to provide a lock for envelops and the like wherein the locking devices are arranged within the envelop or container with all the 30 parts covered so as to be incapable of being operated by an implement or in any way exteriorly of the container.

In the accompanying drawings:

Figure 1 is a plan view of the upper part of an envelop in an open position disclosing 35 an embodiment of the invention applied thereto.

Fig. 2 is a sectional view through the structure shown in Fig. 1 with the parts in a locked position.

40 Fig. 3 is a sectional view through Fig. 2 on line 3—3.

Fig. 4 is a view of the tongue shown in Fig. 1, but illustrating the opposite side thereof.

45 Fig. 5 is a fragmentary sectional view through the tongue shown in Fig. 1, the same being on line 5—5.

Fig. 6 is a view similar to Fig. 1, but showing a modified form of locking means 50 in which the tongue is notched into the flap.

Fig. 7 is a sectional view through the structure shown in Fig. 6 when in a locked position.

Fig. 8 is a sectional view through Fig. 7 55 on line 8—8.

Fig. 9 is a view similar to Fig. 8, but dis-

closing a further modified form of the invention.

In the accompanying drawings an envelop has been illustrated in order to show 60 how the invention is formed and how it may be used to lock a container closed. In illustrating the invention on an envelop in the drawing several forms have been disclosed, all of which act in a similar manner 65 for locking the flap of the envelop closed, and all of which are arranged to be easily manipulated and inserted through an opening when being moved to a locked position.

Referring to the accompanying drawings 70 by numerals, 1 indicates an envelop which is formed substantially in a usual manner and in order that the body of the envelop may not be opened metallic cleats 2, 3 and 4 are arranged at suitable points to clamp 75 the parts together in addition to the usual adhesive provided. The envelop 1 is provided with a flap 5, of any usual or preferred structure, which flap is provided with an adhesive 6 so that the flap may be pasted 80 down in the usual manner. The body 1 is provided with a slot 7 adjacent the cleat 4, which assists in stiffening the body at this point. This slit is designed to receive the tongue 8 which tongue may be part of the 85 flap 5 or a member connected therewith, preferably, however, the back section 9 is formed integral with flap 5 while the front section 10 is of some other material secured in place by an adhesive and also by 90 a metal cleat 11. Arranged between these front and back members are the end sections 12 and 13 of a locking member 14, which locking member is preferably tapered 95 slightly so as to come to a rounded point 15 whereby it more readily hooks over the edge of the slot 7 when the tongue 8 is inserted through said slot. From Fig. 4 it will be noted that a covering of adhesive is arranged on the back of the tongue 8 and the 100 adhesive matter 6 extends over the front of the tongue as shown in Fig. 1.

In operation, after the envelop 1 has received its contents the adhesive covers 6 and 16 are moistened and the tongue 8 slipped 105 into slot 7 until the point 15 snaps over the edge of the slot 7 after which the tongue is withdrawn slightly until the parts assume the position shown in Figs. 2 and 3. The flap 5 is then pressed against the body 1 110 along the portion containing the adhesive 6, and also the body 1 is pressed over that

part of the tongue carrying the adhesive covering 16 whereupon the tongue is caused to adhere to the interior surface of the body of the envelop 1 while the flap 5 adheres to the exterior surface of the envelop. This provides a good fastening means in addition to the lock consisting of the locking member 14 and associate parts. After the envelop has been locked as just described it cannot 10 be opened without injuring some of the parts, which will show that it has been tampered with. It is, of course, known that adhesive may be loosened by steam or other means, but the cleats 2 to 4, cleat 11 and the 15 locking member 14 cannot be disengaged by heat or by any instrument without injuring or mutilating in some manner the envelop. It will be noted that the ends of the cleats 2 and 3 are within the envelop so that these 20 cleats cannot be removed without injuring the envelop, and it will also be noted that member 14 is entirely within the envelop and therefore cannot be tampered with.

In Figs. 6, 7 and 8 will be seen a modified form of the invention in which the flap 17 is cut away at 18 whereby the tongue 20 is in a certain sense set into the flap. This tongue is formed in a similar manner to the tongue 8 except that the reinforcing member 10' is comparatively long. The locking member 14' is also slightly different in construction as it is bent over at 21 and 22, and the bent over section connected by a cross bar 23, which provides a form of wide hook 30 adapted to hook over part of the envelop adjacent the slot when a slot similar to slot 7 is used. However, in this form of the invention a special pocket 24 is provided. This pocket is preferably formed from a 35 single piece of paper or other material and is provided with a body 25 pasted or otherwise secured to the interior surface of the body of the envelop with the lower end of the body adjacent the slot 7'. The part of 40 the material below the body 25 is looped or folded so as to produce a socket 26, said socket being flattened and the overlapping flap 27 secured by an adhesive so that a tapering narrow socket will be produced extending from the slot 7' inwardly substantially parallel with the body of the envelop. When the locking member 14' and the 45 tongue 20 are inserted through slot 7, said locking member and tongue will pass automatically into the socket 26 and locking member 14' emerged therefrom so as to be

hooked over the lower edge thereof as shown in Fig. 8. Preferably the socket member 26 is made from comparatively stiff paper, though it may be made from other material, 60 but when made from this material it will be somewhat resilient whereby as the locking member 14' is passed therethrough it will give, but as soon as the socket member has been moved to the position shown in Fig. 65 8 the parts will automatically move back and consequently the locking member 14' cannot be either intentionally or accidentally removed either by an authorized or an unauthorized person. 70

In Fig. 9 will be seen a modified form of the structure shown in Fig. 6 in which a locking member 14'' is formed with resilient arms 28 and 29 merging into hooks 30 and 31 adapted to snap over the opposite edges 75 of the socket 26 when forced into a locked position. As shown in Fig. 7 the hook part of the lock 14' extends inwardly so that if an implement was forced through the slot 7' it could not affect the hook member unless 80 part of the envelop was torn. The same is true of the structure shown in Figs. 1 to 3. In Figs. 2 and 3 it will be observed that the envelop around slot 17 is reinforced by member 32 which may be cloth, paper, or 85 other suitable material held in place by an adhesive. In Fig. 1 the cleats 2 and 3 face inwardly and thereby prevent any removal while the same arrangement is provided in Fig. 6, though this form of envelop is such 90 that the cleats are covered by the flap 17 which presents an additional safety structure. It will be noted that in all the forms of the invention the metallic clips grip parts of the hook or locking members so that they 95 cannot be released by steaming or in any other way.

What I claim is:—

As a new article of manufacture, an envelop of the conventional shape, the body 100 having a horizontal slot and provided on its inner face with a pocket open at the bottom, the closing flap being provided on each side of its center with substantially V-shaped notches, whereby a comparatively long integral and tapering tongue is formed, the tongue being provided with a hook projecting from its end, said hook engaging the pocket over the edges of the bottom thereof when the envelop is sealed by inserting the 105 tongue through the slit and the pocket. 110

GEORGE DOUTNEY.
